(57) **CLAIM**

The ornamental design for a handle for canister vacuum cleaner, as shown and described.

DESCRIPTION

FIG. 1 is a right side perspective view of a handle for canister vacuum cleaner showing my new design;

FIG. 2 is a front view thereof;

FIG. 3 is a right side view thereof;

FIG. 4 is a rear view thereof;

FIG. 5 is a left side view thereof; and,

FIG. 6 is a top view thereof.

The broken lines in the Figures are for illustrative purposes only and form no part of the claimed design.
